UNITED STATES PATENT OFFICE.

HUBERT HIGGINS, OF CAMBRIDGE, ENGLAND.

COOKING, DRYING, OR STERILIZING BY STEAM.

SPECIFICATION forming part of Letters Patent No. 597,978, dated January 25, 1898.

Application filed August 10, 1897. Serial No. 647,700. (No model.)

To all whom it may concern:

Be it known that I, HUBERT HIGGINS, a subject of the Queen of England, residing at Cambridge, England, have invented certain new and useful Improvements in or Relating to Cooking, Drying, or Sterilizing by Steam, of which the following is a specification.

The object of this invention is to provide an improved apparatus for cooking food or drying any substance or sterilizing animal or vegetable substances by means of steam, whereby in the same apparatus a constant current of steam may be employed at a temperature of about 100° centigrade or at any temperature above that point desirable for the purpose above mentioned, the steam in all cases being kept substantially at atmospheric pressure.

In the method of steam-cooking generally in use the food is placed in a chamber or chambers into which the steam is introduced at a greater or less pressure. In most cases no provision is made to avoid the condensation of the steam, (the food thereby becoming wet,) and in cases where temperatures above 100° centigrade are employed cumbersome and expensive chambers are necessary in order to resist the high pressure, which is a source of inconvenience and even danger in unskilled hands.

In no case are means provided to regulate the temperature of the cooking-chamber to suit the requirements of different culinary operations—such as cooking, roasting, and baking—necessitating varying degrees of heat.

The apparatus employed in carrying out this invention comprises a chamber and a steam-superheater, with the necessary heating apparatus and steam-generator.

The accompanying drawing shows, diagrammatically, a chamber and superheater constructed according to this invention.

The chamber consists of an inner chamber A, preferably completely surrounded by an outer chamber B of somewhat larger size, forming what is commonly known as a "jacket."

The chamber A may be of any suitable size and material and provided with shelves or other fittings according to the purpose for which it is intended, such as cooking, drying, or sterilizing. Proper provision is made

for doors, and it is connected by the pipe D with the superheater C, a pipe A' being likewise provided for carrying away the steam. 55

The superheater may be of any ordinary construction that gives a travel of the desired extent to the steam, and is provided with openings controlled by valves at various portions of its length, so that the steam can be withdrawn at will after a greater or less exposure to the heating medium. A convenient form consists of a coil, as shown at C, receiving its steam through the valve C' and having openings controlled by valves C² C³ C⁴ C⁵ 65 into the pipe D, connected with the chamber A. The coil may be of any convenient form, either helical, as shown, or consisting of zig-zag or parallel tubes united by return-bends, and may be of varying cross-section and caliber, the essential point being the faculty of controlling the length of travel of the steam when exposed to the heating medium. Four connections are shown as a convenient number, but more or less may be used, according 70 to the range of temperature which it may be desired to employ in the chamber.

The superheater may be heated in any convenient manner, either directly by a gas or other furnace or by the products of combustion from the generator-furnace. 80

The supply of steam to the superheater may be obtained in any convenient manner, either from a generator forming part of the apparatus, and which may be either an ordinary 85 boiler or a special arrangement—as, for instance, a tube or system of tubes, part forming the generator and part the superheater—in which case the steam is produced at or about atmospheric pressure, or from generators primarily intended for other purposes, such as the main boilers of a factory or of a steamship. In the latter case a reducing-valve C⁶, of any ordinary construction, is provided in addition to the valve C', so as to reduce 90 the high-pressure steam to any desired extent before its entry into the superheater.

In order to prevent condensation of steam within the chamber A, it may be provided with a jacket B, heated either (a) by passing 100 through it the whole or a sufficient proportion of the combustion-gases from the heating apparatus of the boiler or superheater, or (b) by the direct application of heat to the exterior

of the jacket, or (c) by passing a current of steam from the superheater through the jacket previous to the introduction of steam into the chamber. The necessary pipes, dampers, &c., are provided in each case, so that the temperature is under control, and the outer wall of the jacket is preferably lagged.

The pipe D may be connected direct with the steam-supply by a valve D', so that, if desired, 10 steam may be passed through the chamber without first passing through the superheater. If the steam is obtained from a high-pressure supply, this connection must be supplied with a reducing-valve, so that only low-pressure 15 steam is admitted to the chamber.

All necessary gages, pyrometers, and fittings are provided for properly working and controlling the apparatus.

Two or more chambers may be used and 20 the steam passed from one to the other, a superheater being provided between each chamber, if desired. When a series of several chambers is employed, the necessary connections are provided, so that any one chamber 25 can be disconnected without stopping the circulation of steam through the rest of the series.

When in operation, the jacket B is first heated, so as to warm the chamber A and prevent 30 condensation on the initial admission of steam therein, and this heating may be continued throughout the operation, if desired. Steam having been admitted to the superheater C through the valve C', one of the cocks 35 C² C³ C⁴ C⁵ is opened, and a continuous current of steam passes into the chamber A through the pipe D, escaping therefrom by the valve A'. According as the temperature is required to be raised or lowered the steam 40 is allowed to travel through a greater or less length of the superheater. If a temperature is required only slightly in excess of 100° cen-

tigrade, the cock C² is opened, and the steam passes through only a short portion of the superheater before entering the chamber A 45 through the pipe D. To raise the temperature, the cock C³ is opened and C² closed, giving the steam a longer exposure to the heating medium, the highest temperature being obtained by passing the steam through the 50 whole length of the superheater by opening the cock C⁵, the others being closed. By this means a perfect control of the temperature within the chamber is obtained. The temperature is still further capable of being 55 raised by passing a larger volume of steam through the superheater and allowing it to be carried off by an orifice of suitable size in the chamber. (This does not materially increase the pressure in the chamber.) 60

I claim—

1. In an apparatus for cooking &c., by steam, the combination with a receptacle or chamber, of a superheater, connected to said receptacle, and means for varying the extent 65 of travel of the steam through the superheater, whereby steam at varying temperature may be delivered to the receptacle or chamber; substantially as described.

2. In an apparatus for cooking &c., by 70 steam, the combination with the receptacle or chamber, of a pipe for delivering steam to said chamber, a superheater having communication at various portions of its length with said pipe and valves for controlling communication between said superheater and pipe; 75 substantially as described.

In testimony whereof I have hereto set my hand in the presence of the two subscribing witnesses.

HUBERT HIGGINS.
